UNITED STATES PATENT OFFICE

116,454

DESIGN FOR A COMBINED COOLING AND
SERVING CABINET

Vincent F. Vaclavik, St. Louis, Mo.

Application March 2, 1939, Serial No. 83,288

Term of patent 14 years

To all whom it may concern:

Be it known that I, Vincent F. Vaclavik, a citizen of the United States, residing at St. Louis, State of Missouri, have invented a new, original, and ornamental Design for a Combined Cooling and Serving Cabinet, of which the following is a specification, reference being had to the accompanying drawing forming a part thereof, in which:

Fig. 1 is a top plan view of a combined cooling and serving cabinet showing my new design;

Fig. 2 is a front elevational view; and

Fig. 3 is a side elevational view.

The dominant features of the design reside in

the portion designated *a* in Fig. 1 which is a compartment extending down from the top thereof having a series of circular wells at the back part thereof; the portions *b* which are circular wells; the portion *c* which is a drainboard; and the portions *d* which are sumps, all having the particular appearance and arrangement with respect to the remainder of the cabinet, as shown.

I claim:

The ornamental design for a combined cooling and serving cabinet, as shown and described.

VINCENT F. VACLAVIK.
